[57] CLAIM

The ornamental design for a heating apparatus, as shown and described.

DESCRIPTION

FIG. 1 is a front perspective view showing the new design; FIG. 2 is a front elevation view thereof;

FIG. 3 is a side elevation view thereof, the opposite side being a mirror image;

FIG. 4 is a top plan view thereof;

FIG. 5 is a bottom plan view thereof; and,

FIG. 6 is a rear elevation view thereof.

The broken lines showings of the grille pattern, the tank and stand are for illustrative purposes only and form no part of the claimed design.
